W. C. HUSS.

WALL FIXTURE FOR COUNTERS.

No. 23,454.

Patented July 10, 1894.

UNITED STATES PATENT OFFICE.

WILLIAM C. HUSS, OF CINCINNATI, OHIO.

DESIGN FOR A WALL-FIXTURE FOR COUNTERS.

SPECIFICATION forming part of Design No. 23,454, dated July 10, 1894.

Application filed June 2, 1894. Serial No. 513,334. Term of patent 3½ years.

To all whom it may concern:

Be it known that I, WILLIAM C. HUSS, a citizen of the United States and a resident of Cincinnati, in the county of Hamilton and State of Ohio, have invented a certain new and useful Design for Wall-Fixtures for Counters, of which the following is a specification.

My invention is a new and original design for wall fixtures for counters, the leading features of which are the end columns resting upon the sideboard top and supporting half arches, the arch supporting the entablature at the ends, and the intermediate columns and supports resting upon the top and apparently supporting the entablature at the termination of the curved portion of the arch upon each side, as clearly shown in the accompanying drawings, in which—

Figure 1 is a front elevation of one half of the fixture; and Fig. 2 a vertical transverse section of the same taken through line α - α of Fig. 1, looking toward the end of the fixture.

The top, A, of the sideboard is supported at the front corners by pilaster columns, A', surmounted by plain caps, a, the necks of the columns being enriched by vertical flutes or beads. The base of the sideboard is plain, same as the base of the pilaster, except that the top is molded, the molding returning around the pilaster column at the base.

The front of the pilaster has a molded frame forming panels, and the doors, a', have similar panels of corresponding design. These doors, of which there are two, form closed closets, and there are three doors, a'', upon the opposite side of the narrow column, a'', which have transparent panels. The column, a'', has a central vertical flute, the upper portion above the flute being ornamented by foliage springing from the corners of the column up to the molding underneath the top, A. The base of the column, a'', is also the return of the base of the sideboard, and projects beyond it in a plane with the front of the end pilaster.

The short heavy columns, B, which support the end of the upper portion of the fixture are surmounted by capitals, b, which are carved in scroll foliage. The molded base, b', of the column rests upon the short pedestal, b'', which flares out at each side from the base,

and then follows in a vertical line to the sideboard top, the corners of the pedestal being chamfered off in an ogee curve.

Above the columns, a'', on the sideboard top 55 rests the pedestal, c, which supports a pair of tapering rectangular columns, C, surmounted by carved capitals, c', covered by a single abacus, upon top of which rest the cluster columns, c'', which are surmounted by carved 60 capitals, upon which the architrave apparently rests at the termination of the curved portion of the arch. A short shaft, c'', rests upon the top of these capitals and breaks the lower fascia, d, of the architrave. Upon this 65 short column is a molded capital of the same shape as the upper fascia, d', of the architrave, which breaks said fascia, the molding returning around, forming the cap. The lower fascia, d, after it passes the straight or 70 horizontal portion of the architrave, curves down, forming the front of the arch and rests upon the capital, b, being returned to the end of the fixture, while the upper fascia, d', extends in a horizontal line to near the end and 75 returns in a rounded corner to the rear or wall, the upper and lower fascia forming a spandrel or irregular space, d''. The corner is enriched by a grotesque head, of which the tongue protrudes and supports an incandescent globe, e. The leg terminates in a claw, which rests upon the top of the returned piece, d, and the wings, which extend upon the front and ends, are ornamented with 80 carved foliage.

The cornice, F, is the same shape in cross section as the outline of the capital, F', which rests upon the fluted column, f, the base of which rests upon the upper fascia of the architrave. The column and its capital return 85 around the corner of the frieze and cornice, and the end of the fixture extending back to the wall is finished the same as the front of the entablature. From the column a scroll ornament springs and rests upon the frieze, 90 G. The cornice, F, is apparently supported by carved modillions, f', at regular intervals.

On the frieze, vertically above the intermediate columns, is an ornamental panel, g, corresponding in finish to the panels upon the 100 pilaster and doors of the sideboard portion, and in the center of the frieze is an orna-

mental foliage, having a ribbon or streamer extending from its corner out upon each side of the frieze. The under side of the arch and architrave is finished with transverse, reflecting, bevel edged panels, *h*, and the lower fascia of the architrave is bordered by an ornamental astragal molding, *d*³. The back of the fixture within the arch is a framed mirror, *I*.

What I claim as new, and desire to secure by Letters Patent, is—

The design for wall fixture for counters substantially as shown and described.

WILLIAM C. HUSS.
